(57) **CLAIM**

The ornamental design for a microphone, as shown and described.

DESCRIPTION

FIG. 1 is a right side view of a microphone according to my new design;

FIG. 2 is a bottom plan view thereof;

FIG. 3 is a left side view thereof;

FIG. 4 is a top plan view thereof;

FIG. 5 is a rear view thereof;

FIG. 6 is a front view thereof;

FIG. 7 is a three-dimensional perspective view thereof;

FIG. 8 is a three-dimensional right side view thereof;

FIG. 9 is a three-dimensional left side view thereof;

FIG. 10 is a three-dimensional bottom plan view thereof;

FIG. 11 is a three-dimensional top plan view thereof;

FIG. 12 is a three-dimensional rear view thereof; and,

FIG. 13 is a three-dimensional front view thereof.

The broken lines shown in the drawings form no part of the claimed design.
